UNITED STATES PATENT OFFICE.

WALTER A. GARRIGUS AND ROBERT GOLLING, OF ST. ELMO, TENNESSEE.

TOOL-HOLDER.

No. 828,026.

Specification of Letters Patent.

Patented Aug. 7, 1906.

Application filed April 25, 1905. Serial No. 257,851.

To all whom it may concern:

Be it known that we, WALTER A. GARRIGUS and ROBERT GOLLING, citizens of the United States, residing at St. Elmo, in the county of Hamilton and State of Tennessee, have invented a new and useful Tool-Holder, of which the following is a specification.

The invention relates to improvements in tool-holders.

10 The object of the present invention is to improve the construction of tool-holders, and to provide a simple and comparatively inexpensive one of great strength and durability designed particularly for holding thread-cutting dies, taps, and other tools and adapted to permit the dies or other tools to be quickly changed when desired.

15 A further object of the invention is to provide a tool-holder of this character adapted to be readily arranged for operation in a corner or close to an obstruction, where there is but little room.

20 Another object of the invention is to arrange the parts so that when the tool-holder is operated the means for detachably retaining the dies or other tools in the stock will not be subjected to any strain.

25 With these and other objects in view the invention consists in the construction and 30 novel combination and arrangement of parts hereinafter fully described, illustrated in the accompanying drawings, and pointed out in the claims hereto appended, it being understood that various changes in the form, proportion, size, and minor details of construction within the scope of the claims may be resorted to without departing from the spirit or sacrificing any of the advantages of the invention.

35 In the drawings, Figure 1 is a plan view of 40 a tool-holder constructed in accordance with this invention and arranged for cutting threads on a screw. Fig. 2 is a longitudinal sectional view of the same. Fig. 3 is a longitudinal sectional view of the central portion of the tool-holder, the section being taken at right angles to Fig. 2. Fig. 4 is a detail perspective view of the rotary die-carrying head. Fig. 5 is a perspective view of the tool-holder, 45 one of the handles being removed to permit the tool-holder to operate in a corner or close to an obstruction. Fig. 6 is a plan view of the tool-holder, a tap or tool-carrying head being substituted for the die-carrying head.

Fig. 7 is a longitudinal sectional view of the 55 same. Fig. 8 is a perspective view of the tap or tool carrying head.

Like numerals of reference designate corresponding parts in all the figures of the drawings.

1 designates a cylindrical casing forming the central portion of the stock of the tool-holder and provided at diametrically opposite points with integral projections 2 and 3. The projection 2, which is solid, is provided 60 with exterior screw-threads 4 and is adapted to receive an interiorly-threaded hollow handle 5. The short exteriorly-threaded projection is solid in order to secure the necessary strength, and as it is exceedingly short, particularly when compared with the other projection 3, which is hollow, it does not interfere with the operation of the tool-holder in a corner or close to an obstruction when the handle 5 is removed, and the tool-holder 65 is arranged as illustrated in Fig. 5 of the drawings. The tool-holder is then adapted to oscillate back and forth as a ratchet wrench or tool, as hereinafter more fully explained.

70 The hollow projection 3 is provided at its outer end with interior screw-threads 5^a and is adapted to receive an exteriorly-threaded hollow handle 6 of the same diameter as the said handle 5. Within the hollow projection 75 is arranged a ratchet-dog 7, having a tooth 8 and adapted to engage a circular rotary head 9, removably arranged within the cylindrical casing and provided with peripheral teeth 10. The tooth of the ratchet-dog is beveled at one 80 face and is provided at the opposite face with a shoulder and is adapted to be reversed for reversing the ratchet action of the tool-holder. The dog is provided with an annular groove 11, and it has diametrically opposite longitudinal grooves 12 and 13, adapted to receive a projection 14 of a pin or screw 15. The pin or screw 15, which is mounted in a threaded perforation of the hollow projection, 85 extends inwardly from one of the walls thereof, and it is adapted to guide the ratchet-dog 90 in its reciprocating movement. The dog is maintained in engagement with the rotary head by a coiled spring 16, disposed on a rod or stem 17 and interposed between the dog 95 and a cap 18, which is fitted on the outer end of the hollow handle 6. The cap is provided 100 with an aperture through which the stem 17

passes, and the stem, which projects beyond the cap, is provided with a thumb-piece or grip 19, adapted to be readily grasped by the operator for drawing the ratchet-dog outwardly 5 to bring the annular groove 11 opposite the projection 14 to permit the dog to be partially rotated for reversing it. By this construction the tool-holder may be arranged for rotating the head 9 in either direction 10 when the said tool-holder is oscillated.

The cylindrical casing is provided at the back with an inwardly-extending annular flange 20, forming a seat for the rotary head 9, and the front side of the casing is entirely 15 open, the front face or edge of the casing being flush with the outer or front face of the head 9. The teeth 10 of the head extend entirely across the periphery thereof, and the intervening transverse grooves, which receive the dog, extend entirely across the periphery of the head, so that the said head may be readily removed from the casing. It is prevented from dropping out of the casing when the tool-holder is not in use by 20 means of a screw 21, having a cam-head mounted in a threaded aperture of the casing at one side of the opening or chamber thereof and adapted to project inward over the rotary head, as clearly illustrated in Figs. 1, 25 30 and 5 of the drawings. The cam-head is adapted to be turned to release the head 9, which will drop out of the casing when the tool-holder is inverted. When the tool-holder is operated, the ratchet-dog and the 35 teeth of the rotary head sustain all the strain and the cam-screw is not subjected to any strain.

The rotary head 9 is provided with a central opening for the reception of thread-cutting dies 22, which are retained in the head 40 by means of suitable screws 23 or other suitable fastening devices. Each set of dies is designed to be arranged in a separate head, so that the dies may be quickly changed by 45 simply removing one head and substituting therefor another having dies of a different size. In this manner the dies may be changed without any adjustment thereof, and the removal of the dies does not affect 50 their adjustment.

The casing is also adapted to receive a rotary head 24, as illustrated in Figs. 6 and 7 of the drawings, having an inner circular portion adapted to fit within the casing and provided with teeth 25, extending entirely 55 across the periphery of that portion of the head 24 lying within the casing, and the intervening grooves extend to the rear face of the head 24, so that the dog will not interfere 60 with the removal of the head. The rotary head 24 is provided with an extension 26, and it has an annular groove 27 to receive the cam-headed screw 21 before described. The projecting portion or extension is provided

in its outer face with a dovetailed way 28, 65 extending entirely across the head and having oppositely-inclined walls for retaining a pair of adjustable jaws 29 and 30 in the way. The jaws are adjusted by means of opposite screws 31, mounted in threaded apertures of 70 ears or projections 32 of a collet or rim 33. The collet or rim 33 is arranged on the projecting portion of the head 24 and is secured to the same by screws 34 or other suitable fastening devices. The outer ends of the 75 jaws are engaged by the adjusting-screws, and the inner ends or engaging portions of the jaws are adapted to grip a tap or other tool, and the jaw 29 is provided in its engaging portion with a V-shaped recess, the angularly-disposed faces of which extend from the median line to the side edges of the jaw. The other jaw 30 has its engaging portion tapered to fit the recess 35 of the jaw 29 and is provided with a central V-shaped notch 36 80 for engaging one of the corners of a squared tool-shank. The jaws are readily adjusted for clamping a tap, a nut-receiving socket, or other tool, as will be readily understood, and the tool-receiving head 24 may be quickly 85 detached when it is desired to use a die-receiving head.

Having thus fully described our invention, what we claim as new, and desire to secure by Letters Patent, is—

1. A tool-holder, comprising a casing provided at opposite points with integral projections, one of the projections being hollow, and the other projection being solid, and the solid projection being shorter than the other, 95 a rotary head fitted within the casing and provided with teeth, ratchet mechanism for engaging the teeth, and hollow handles secured to the said projections, the handle of the solid projection being removable to permit the tool-holder to operate in a corner or close to an obstruction.

2. A tool-holder, comprising a casing provided at opposite points with long and short integral projections, the short projection being solid, a rotary head mounted in the casing, ratchet mechanism for engaging the head, and handles secured to the said projections, the handle of the solid projection being, removable to permit the tool-holder to operate in a corner or close to an obstruction.

3. In a tool-holder, the combination of a stock having a casing open at one face and provided at the opposite face with a projecting flange forming a seat, a ratchet-dog mounted in the stock at the casing thereof, a removable rotary head fitted in the casing and provided with an intermediate annular groove and having teeth extending inward across its periphery beyond the dog to the 120 inner face of the head at the flange or seat of the casing, so that the head may be withdrawn from the casing without first disen-

gaging the dog from it, said groove being located at the open face of the casing and the outer portion of the rotary head lying entirely beyond the same, and a cam-headed screw mounted on the casing at the open face thereof and engaging the groove of the rotary head.

In testimony that we claim the foregoing

as our own we have hereto affixed our signatures in the presence of two witnesses.

WALTER A. GARRIGUS.
ROBERT GOLLING.
